UNITED STATES PATENT OFFICE.

JURDON R. PHELPS, OF WACO, TEXAS.

FILING MACHINE.

Application filed November 19, 1924. Serial No. 750,896.

This invention relates to a saw filing machine, the general object of the invention being to provide means for feeding the saw step by step and means for reciprocating a file with means associated with the file operating means for lifting the file off the saw so that the saw holding means can be moved and then placed in engagement with the saw before it is given its cutting stroke.

Another object of the invention is to provide means for adjusting the saw holding means to cause the file to give the tooth its proper cutting angle and means for causing the device to move the saw in either direction as desired.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of the device.

Figure 2 is a side view thereof.

Figure 3 is a section on line 3—3 of Figure 2.

In these views 1 indicates a base which is supported by the legs 2 and which supports the casing 3 and the posts 4, a top plate 5 being supported by a part of the casing and the posts. A shaft 6 passes through the casing 3 and has at one end thereof a hand wheel 7 and its other end a grinding wheel 8. The wheel 7 is provided with the ring gear 9 and stub shafts 10 and 11 are journaled in the casing 3 and have pinions 12 thereon which mesh with the gear 9. Thus the stub shafts 10 and 11 will be rotated when the main shaft is rotated from the hand wheel. A crank disc 13 is connected with the inner end of each stub shaft. A cam 14 is connected with the crank disc of the upper shaft. A guideway 15 is formed on the front end of top plate 5 and a block 16 is slidably mounted therein. This block carries a shaft 17 which is provided with a socket 18 for receiving a saw file 19 and the inner end of said shaft is pivoted as at 20 to a pitman 21 which is fastened to the crank pin of the upper disc 13. Thus the file is reciprocated by the rotary move-

ment of the crank disc and in order to raise the file out of engagement with a saw on one stroke of the file I pivot a lever 22 to a bracket 23 depending from the top plate and this lever has one end adapted to be struck by the cam 14 so that it will be rocked on its pivot and its other end is bent upwardly as at 24 and passes through the guideway and engages the block so that it will force the block upwardly and thus raise the file and its shaft, as shown in dotted lines in Figure 2, when the lever is rocked by the cam. The parts are normally held in lowered position by means of the spring 25. A saw holder 26 has a slot 27 therein to receive a saw, such as shown at A, the saw being clamped in the holder by means of the thumb nuts 28 on the bolts 29. The holder is slidably mounted in a guideway member 30 which is pivoted at its center to the base 1, as shown at 31. An arc-shaped brace 32 has its ends connected with the ends of the member 30 and this brace passes through the clamps 33 on the base so that the parts can be adjusted to the desired position and then clamped in this position. A block 34 is pivoted to the base plate and has a guideway therein for receiving a head 35 to which the caliper-like arms 36 are pivoted, the arms being normally held against the stop pins 37 on the block by the spring 38 which connects the two arms together. These arms act as dogs on the ratchet wheels 39 which are mounted on a vertical stub shaft 40 to which a gear 41 is fastened which engages a rack 42 on the saw holder 26. The head 35 is connected by the turn-buckle device 43 with the pitman 44 which is connected with the crank pin of the lower crank disc. The block 34 can be adjusted by means of a screw shaft 45 which passes through a threaded hole in a post 46 on the base plate, the inner end of the shaft being connected with an extension 47 of the block. Thus by turning the shaft 45 by its handle 48 the block 34 can be rocked on its pivot so as to bring either one of the dogs or arms 36 in engagement with its ratchet and as these ratchets are oppositely arranged when one ratchet is being operated by its dog it will turn the shaft 40 in one direction and thus cause the saw holder to move in one direction while when the other ratchet is in action the shaft is turned in another direction and the saw holder is moved in an

opposite direction from that given it by the first ratchet.

As will be seen by turning the hand wheel the saw holder will be given a step by step movement and the file will be reciprocated, the file on one stroke engaging the teeth and on its other stroke being raised out of engagement with the saw so that the saw can be moved by the ratchet means above described. Thus the saw can be sharpened by simply turning the hand wheel and the parts can be adjusted to give the cutting edges of the teeth the proper angle. The grinding disc 8 may be used for sharpening various tools.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

25 A saw filing machine comprising a supporting frame, a hand wheel having a shaft journaled in the frame, a gear on the wheel, a pair of stub shafts, pinions thereon engaging the gear, a crank disc on each stub shaft, a slidable block on the frame, a file

carrying shaft connected with the block, a pitman pivoted to the shaft and connected with the upper crank disc, a cam on said crank disc, a lever pivoted to the frame and engaged by the cam and having a part 35 for engaging the block for raising the same to lift the file, a saw holder, a guideway for the same, means for adjusting the guideway on the frame to place the saw at any desired angle in relation to the file, a rack 40 on the holder, a shaft in the frame, a pinion thereon engaging the rack, a pair of oppositely arranged ratchets on the shaft, a head, a pair of dogs thereon for engaging the ratchets, a block pivoted to the frame 45 and moved about a vertical axis and having a horizontal guideway therein in which the head is slidably mounted, adjustable means for connecting the head with the lower crank disk, an extension on the inner end 50 of the block, a screw shaft connected with the extension and a post on the frame having a threaded hole therein through which the shaft passes so that by turning the shaft the block will be rocked on its pivot to bring either dog into engagement with its ratchet.

55 In testimony whereof I affix my signature.

J. R. PHELPS.
